UNITED STATES PATENT OFFICE.

CHARLES H. STEVENSON, OF WALLINGFORD, CONNECTICUT, ASSIGNOR TO WINCHESTER REPEATING ARMS CO., OF NEW HAVEN, CONNECTICUT, A CORPORATION.

TUBULAR SHOT-CARTON.

1,113,708.

Specification of Letters Patent.

Patented Oct. 13, 1914.

Application filed October 2, 1913. Serial No. 792,936.

To all whom it may concern:

Be it known that I, CHARLES H. STEVENSON, a citizen of the United States, residing at Wallingford, in the county of New Haven and State of Connecticut, have invented a new and useful Improvement in Tubular Shot-Cartons; and I do hereby declare the following, when taken in connection with the accompanying drawings and the characters of reference marked thereon, to be a full, clear, and exact description of the same, and which said drawings constitute part of this application, and represent, in—

Figure 1, a view in side elevation of a tubular shot-carton constructed in accordance with my invention, with its split annular gate in its open position. Fig. 2, a view thereof in central longitudinal section on the line *a—b*, of Fig. 1. Fig. 3, a broken view of the carton in side elevation with its gate in its closed position. Fig. 4, a detached plan view of the gate.

My invention relates to an improvement in tubular shot-cartons, the object being to produce a simple, convenient and reliable tubular carton constructed with particular reference to low cost of production.

With these ends in view, my invention consists in a tubular shot-carton having certain details of construction as will be hereinafter described and pointed out in the claim.

In carrying out my invention as herein shown, I employ a split annular gate in the form of a resilient wire ring, 2, split to form a shot-opening 3, and adapted to be sufficiently sprung to be passed over a paper tube 4 which is formed for the reception of the said ring 2 with a seat consisting of a circumferential groove 5 in which the ring seats itself against lateral movement but with a capacity for being rotated with respect to the longitudinal axis of the tube which is also formed with a circular feeding-opening 6 intersecting the said groove 5 and sufficiently large for the passage through it of the contained shot 7. It will be noted that the diameter of the wire used for producing the gate is smaller than the diameter of the feeding-opening 6 which the gate diametrically crosses, so that while the gate

discharges its function of confining the shot in the carton, it still permits the shot to be seen through the feeding-opening. The tube itself may in other respects be of any suitable construction. As herein shown, its ends are crimped inward as at 8 for the retention in place of wads 9 which close its ends. The gate 2 is normally turned so as to carry its shot-opening 3 out of registration with the feeding-opening 6 as shown in Fig. 3, whereby none of the shot 7 are allowed to escape through the said feeding-opening. On the other hand, when it is desired to remove the shot, the gate is rotated until its shot-opening 3 is brought into registration with the opening 6, after which the shot may be poured out of the carton in a single stream.

My improved tubular shot-carton may be produced at a very low cost, since it is merely necessary to form its paper tube with a circumferential seat for the reception of the gate which, being resilient and split, has only to be sprung over one end of the tube and slid thereupon until it reaches its seat when it snaps thereto and hugs the bottom thereof with a sufficient grip to hold it against turning except when it is manually turned for the registration of its shot-opening with the feeding-opening in the carton.

I claim:

As a new article of manufacture, a tubular paper shot-carton comprising a paper cylinder having rounded, rimless ends and formed near one end with a depressed circumferential seat having a feeding-opening located in its bottom, a rotatable annular gate located in the said seat and formed with a shot-opening co-acting with the said feeding-opening, the said gate being formed from a single piece of wire smaller in cross-sectional diameter than the diameter of the feeding-opening, and means located within the ends of the paper cylinder for closing the same.

In testimony whereof, I have signed this specification in the presence of two subscribing witnesses.

CHARLES H. STEVENSON.
